CIGARETTE AND VANITY CASE

Ruth Potishman, Fort Worth, Tex.

Application January 11, 1939, Serial No. 250,413

1 Claim. (CL 132—83)

This invention relates to improvements in combined cigarette and vanity cases particularly adapted for use by women, the primary object being to produce an article of this kind which is simple and compact in construction and extremely convenient to use.

The present invention consists in certain novel features of construction and combination and arrangement of parts hereinafter more fully described, shown in the accompanying drawings and claimed.

In the drawings:

Figure 1 is a plan view of a cigarette and vanity case constructed in accordance with the present invention, the case being opened to reveal details of construction.

Figure 2 is an end elevational view thereof in closed condition.

Figure 3 is a transverse section on line 3—3 of Figure 1.

Figure 4 is a transverse section on line 4—4 of Figure 1.

Figure 5 is a front elevational view of the vanity case in closed condition as shown in Figure 2; and

Figure 6 is an enlarged fragmentary section on the plane of line 6—6 of Figure 5.

Referring in detail to the drawings, the present cigarette and vanity case includes a body composed of two similar sections 5 and 5a in the form of shallow oblong trays, and a flat division member 6 disposed intermediate the sections 5 and 5a of the body, the three parts 5, 5a and 6 being hinged together for independent movement along corresponding longitudinal edges as at 7. The body sections 5 and 5a are provided on their remaining or free longitudinal edges with spring catches 8 and 8a adapted to engage the flat division member 6 to releasably secure the latter in closing relation to the body sections 5 and 5a, respectively.

As shown, the division member 6 is preferably in the form of a mirror unit composed of a sheet metal frame having plain and magnifying mirrors 8 and 8a secured therein in side by side relation and on the side thereof facing the body section 5. This body section 5 is divided by a transverse partition wall 10 into two compartments 11 and 11a, the compartment 11 having a powder screen 12 removably fitted therein in spaced relation to the top and bottom thereof. Face powder is adapted to be placed in the compartment 11 below the screen 12 as at 13, and sufficient space is left in the top of the compartment 11 above the screen 12 to receive a powder puff

14. Affixed within the compartment 11a is a pocket member 15 adapted for removable reception of the back member 16 of a package of lipstick tissue 17. In this way, the packet of lipstick tissue is effectively retained in the compartment 11a for convenient use, the supply of tissue being readily replenished by simply removing the back member of the used packet and inserting a new one. The mirror surfaces 8 and 8a facilitate the use of the powder puff, a lipstick, and the lipstick tissues, the powder puff and the lipstick tissues being readily accessible when the catch 8 is released and the division member 6 is swung to the open position of Figures 1, 3 and 4. At this time, the division member 6 may be left in closing relation to the body section 5a with the catch 8a engaged with said division member 6, in which event the section 5a will be effectively closed so as to prevent passage of tobacco from cigarettes in the section 5a into the powder lipstick tissue compartments of section 5.

As shown clearly in Figure 1, the body section 5a is of such dimension as to permit the storage of a number of cigarettes 18 therein, with the cigarettes disposed transversely of the section 5a in side by side relation. Extending longitudinally from end to end of the section 5a near the hinged edge of the latter is a retaining strap 19 under which the cigarettes 18 are engaged and by which they are effectively retained in place until manually withdrawn, as is well known in the art of cigarette cases. It will of course be seen that when access to the powder puff and lipstick tissue is not desired, but access to the cigarettes is desired, the catch 8a may be released so as to permit swinging of the body section 5a to open position, the division member 6 being left in closing relation to the body section 5 as retained by the catch 8. This prevents passage of powder into the cigarette compartment afforded by the section 5a, and it will be seen that the device is extremely simple and compact in construction as well as extremely convenient to use. The division member 6 is in closing relation to both sections 5 and 5a of the body when the parts 5, 5a and 6 are swung together and latched in contiguous relation as shown in Figures 2, 5 and 6. At this time, passage of tobacco into the powder puff compartment or passage of powder into the cigarette compartment is effectively prevented. Individual access to either section 5 or 5a is permitted without opening the other section.

It will be apparent that the invention is susceptible of modifications and such changes in

details of construction as fairly fall within the spirit and scope of the invention as claimed.

What I claim as new is:

5 A cigarette and vanity case including a body composed of two similar sections in the form of shallow oblong trays, and a flat division member disposed intermediate and completely spacing said sections, means hinging said sections and said division member together along corresponding longitudinal edges for independent movement, catches on the remaining longitudinal edges of said sections engageable with said division member to releasably secure the latter in closing relation to said sections, said division member comprising a frame engageable by said catches and having plain and magnifying mirrors secured

therein in side by side relation, a transverse partition dividing one of said sections into two compartments, a powder screen removably fitted in one of said compartments in spaced relation to the top and bottom of the latter, a pocket member affixed within the other compartment for removable retaining reception of the back member of a package of lipstick tissue, the other section being of such dimensions as to permit the storage of a number of cigarettes therein in side by side 10 relation when disposed transversely of the latter section, and a retaining strap for the cigarettes extending longitudinally and from end to end of the latter section near the hinged edge of said latter section. 15

RUTH POTISHMAN.
